UNITED STATES PATENT OFFICE.

HENRY MARTIN, OF EDDYVILLE, KENTUCKY.

HAT BRACE.

Application filed August 24, 1927. Serial No. 215,209.

This invention relates to braces primarily adapted for use within hats to retain the shapes of the crowns therefor.

An object of the invention comprehends a supporting member carried within the sweat band of the hat.

Another object of the invention contemplates a crown engaging portion carried by the supporting member to prevent the crown of the hat from losing its shape.

More specifically stated the support and crown engaging members are adjustably connected to facilitate accommodation of the device upon hats having different heights of crowns.

With the above and other objects in view, the invention further consists of the following novel features and details of construction, to be hereinafter more fully described, illustrated in the accompanying drawings and pointed out in the appended claim.

In the drawings:

Figure 1 is a longitudinal sectional view taken through a crown hat with the invention applied.

Figure 2 is a sectional view taken on line 2-2 of Figure 1.

Figure 3 is a sectional view taken on line 3-3 of Figure 2.

Figure 4 is an elevation of a modified form of the invention.

Figure 5 is a top plan view of the modification.

Figure 6 is an elevation of an additional modification of the invention as applied.

Figure 7 is a sectional view on line 7-7 of Figure 6.

Referring to the drawings in detail, wherein like characters of reference denote corresponding parts, the reference character 10 indicates a substantially inverted T-shaped supporting member, the horizontal leg 11 thereof being curved to conform to the configuration of the hat crown and adapted to be received within a pocket portion as defined in the application of a sweat band to a hat crown. The vertical leg 12 of the supporting member 10 is depressed upon the inner side as indicated at 13 to provide an embossed portion upon the reverse side thereof and adapted for reception within a groove or depressed portion 14 in a vertical leg 15 of a crown engaging member 16.

Clamping sleeves 17 carried upon the adjacent extremities of the vertical legs for the supporting and crown engaging mem-

bers 10 and 16 respectively are adapted to clamp the adjacent legs to prevent the bead or rib from riding out of the groove 14 whereby the leg 15 may be raised vertically of the leg 12 and held against displacement by said sleeves. Outwardly converging arms 18 carried upon the upper end of the vertical leg 15 for the crown engaging member 16 are adapted to be disposed upon the opposed sides of the center crease and the crown of the hat. Penetrating elements 19 carried by the vertical leg 15 between the arms 18 are adapted to engage the lower portion of the crease.

As illustrated in Figure 1 of the drawings, the arms 18 and adjacent portion of the vertical leg 15 are curved to conform to the natural configuration of the hat crown.

The adjustment afforded between the vertical legs of the supporting and crown engaging members is adapted to facilitate application of the invention upon hats having different heights of crowns.

In Figures 4 and 5 of the drawings, I have illustrated a modified form of the invention which is constructed of wire in contradistinction to a flat material, in the instance of the form of the invention as previously described and illustrated, the modification takes the same configuration of the preferred form. The penetrating elements are excluded as well as the clamping sleeves. In the modification the vertical portions thereof are disposed in juxtaposition and parallelism. The extremities thereof are provided with loops 20 adapted to receive the vertical leg of the companion member. Frictional engagement is caused between the leg portions at the points of connection whereby the device will be retained in a desired adjusted position.

In Figures 6 and 7 of the drawings I have illustrated an additional modification of the invention which is essentially the same as the form of the invention as disclosed in Figures 4 and 5 of the drawings, save that successive convolutions or loops 21 are formed upon the extremities of the leg portions of the supporting and crown engaging members to further provide a locking means between the members for the purpose set forth. The extremities of the transverse leg for the substantially inverted T-shaped supporting member terminate to provide upwardly and inwardly curved extremities 22 which are adapted to prevent the ends of the

transverse leg from penetrating the pocket portion, as previously described, in the sweat band.

The invention is primarily designed to prevent hat crowns from being knocked in at the ends or becoming slouched when dampened.

Subsequent to a hat cleaning process and while the hat is still damp from being saturated with different cleaning fluids, any one of the different forms of the invention if applied, immediately thereafter, would retain the original shape of the hat while drying. It is frequently known that persons engaged in the hat cleaning business frequently crease hats in a different manner than that desired by the wearers, in such case the hat is subsequently recreased in a different manner and the initial crease detracts from the desired one.

The invention is designed to retain the original and customary crease of hats and from which various deviations or departures from the same may be effectively accomplished without causing the usual bulges upon radically changing the original configuration of the hat crown.

The invention is susceptible of various changes in its form, proportions and minor

details of construction, and the right is herein reserved to make such changes as properly fall within the scope of the appended claim.

Having thus described the invention, what is claimed is:—

A brace device adapted for use within hats to retain the shapes of the crowns thereof comprising a brace member of substantially inverted T-shaped configuration adapted for reception within a pocket portion behind the sweat band, a crown engaging member having a depending portion disposed in juxtaposition to an upstanding portion of the brace member, the ends of said depending portion and upstanding portion of the brace member being adapted to be lapped one upon the other, arms outwardly converging from and carried by the crown engaging member being adapted to engage and conform to the configuration of hat crowns to retain the crease therein, and said depending portion and upstanding portion being depressed for interfitting engagement to prevent distortion of the device from a desired adjusted position.

In testimony whereof I affix my signature.

HENRY MARTIN.
